UNITED STATES PATENT OFFICE

143,917

DESIGN FOR A PENCIL SHARPENER

Edward C. Hoffmann, St. Louis, Mo.

Application October 22, 1945, Serial No. 123,088

Term of patent 14 years

(Cl. D74—1)

To all whom it may concern:

Be it known that the undersigned, Edward C. Hoffmann, a citizen of the United States, residing at St. Louis, Missouri, has invented a new, original, and ornamental Design for a Pencil Sharpener, of which the following is a specification, reference being had to the accompanying drawing, forming a part thereof, in which:

Fig. 1 is a top plan view of a pencil sharpener showing my new design;

Fig. 2 is a front elevation;
Fig. 3 is a left end elevation; and
Fig. 4 is a right end elevation.

I claim:

The ornamental design for a pencil sharpener, substantially as shown.

EDWARD C. HOFFMANN.
